OTHER PUBLICATIONS

Communication dated Apr. 29, 2013 issued by the Canadian Patent Office in counterpart Canadian Design Patent Application No. 146849.

Primary Examiner — Elizabeth Albert(74) *Attorney, Agent, or Firm* — Sughrue Mion, PLLC(57) **CLAIM**

The ornamental design for a ballpoint pen, as shown and described.

DESCRIPTION

FIG. 1 is a perspective view of front, top and right side of a ballpoint pen showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front exploded view thereof.

The grip and writing tip shown in broken lines in FIG. 8 are included for the purposes of showing portions that form no part of the claimed design.
